UNITED STATES PATENT OFFICE.

HERMAN F. W. HUEG, OF LONG ISLAND CITY, NEW YORK.

BAKE-OVEN.

SPECIFICATION forming part of Letters Patent No. 542,338, dated July 9, 1895.

Application filed January 10, 1895. Serial No. 534,457. (No model.)

To all whom it may concern:

Be it known that I, HERMAN FREDERICK WILLIAM HUEG, a citizen of the United States, and a resident of Long Island City, county of Queens, and State of New York, have invented certain new and useful Improvements in Bake-Ovens; and I declare that the following is a full and exact specification of my invention, reference being had to the accompanying drawings, wherein—

Figure 1 is a perspective view of my improved bake-oven with fermenting-compartment and conveying apparatus. Fig. 2 is a vertical section; Fig. 3, a horizontal section on line 3 3 in Fig. 2. Figs. 4 and 5 are details of carriers and shelves for conveying wares; Fig. 6, a perspective view of damper regulating draft through the oven. Figs. 7, 8, and 9 are details of contrivances for moving and transmitting the carriers from one track to another. Fig. 10 is a vertical and Fig. 11 a horizontal section on line II II in Fig. 10 through the heater, showing the apparatus for heating the oven with gas. Fig. 12 is a vertical and Fig. 13 a horizontal section on line III III in Fig. 12 through the heater, showing the apparatus for heating the oven with oil.

My invention relates to bake-ovens for bread, cakes, rolls, crackers, and other such articles of food; and it consists in the herein-after-described particular construction of an oven with a centrally-located heater and with a fermenting-compartment, of an apparatus for conveying wares in a continuous circuit through the oven and through the fermenting-compartment, and of several minor contrivances appertaining thereto.

To bake bread and similar articles of food thoroughly, and to produce thereby the shiny, brown, and crisp crust which is characteristic of well-prepared bakers' wares, it is absolutely necessary to retain the vapors (sweat) arising from the dough in the process of baking.

Following minutely the process of baking in the pursuit of my trade, I observed, and later convinced myself through practical tests, that the vapors arising from the dough are carried into flues by the current of gases flowing through the oven, and I therefore constructed an oven wherein all connections with flues are avoided, a heater being provided

within the baking-chamber, and but one outlet, closed by a cock-valve, necessary to release superfluous vapors accumulating beneath the top of the baking-chamber in a continuous-baking process.

My improved bake-oven comprises baking-chamber C, with heater B set in its center and dividing it into two compartments C' and C'', communicating above the top of the heater. The oven is built preferably of bricks, with double walls and double decking, outer walls b being about six inches apart from the inner walls c on back and both sides of the oven, the space between the inner and outer walls on these three sides being divided into flues through which the gases produced by combustion of the fuel are conducted up and down around the baking-chamber before they pass into the flue E, leading into the chimney. The space between the outer and inner walls on the front side of the oven is ten to twelve inches wide, and a square water-boiler D is set therein adjoining the heater. This boiler is kept filled with water conducted to it through feed-pipes, and conveniently located faucets permit the withdrawing of the heated water required for preparing the wares and furnishes also the hot water required for heating the fermenting-compartment F beneath the oven. In this manner the unexpended heat of the gases passing through the flues on both sides of the boiler and the heat accumulated in the wall of the heater are economically utilized and the necessity of providing separately a boiler for heating of water required in the bakery and for heating the fermenting-compartment obviated.

The oven may be heated by coal, and then a suitable coal-furnace A, as shown in Fig. 2, is provided in the lower part of heater B. Flues e and e', connecting the furnace directly with a top flue E, are opened when the fire is started to produce a strong draft, clearing away the dense smoke. On top of the furnace, directly over the fire, register Aa is provided, constructed of flat iron bars and opening into the heater. When the fire is clear the flues e and e' are partly or entirely shut and this register Aa opened, the hot gases then passing into the heater and through flue er, near the top of the heater, into the flues provided between the inner and

outer walls of the oven. The oven may, however, be heated also by gas or oil, and for that purpose, in place of a coal-furnace, an oil or gas heating apparatus, such as are used for 5 boilers, may be set.

In Figs. 10, 11, 12, and 13 I have shown the apparatus for heating the oven with gas and oil adapted for this purpose. Aa, in Fig. 10, designates a gas-main pipe, divided into 10 branches Ac, and each of these is again divided into secondary pipes extending upward along the walls of the heater and provided at suitable intervals with elongated burners bb. Bb is an air-pipe, having branches Bc, similarly arranged as the gas-pipes, and outlets connecting with those of gas-pipes on points where burners bb are set. These outlet-pipes deliver a current of air into the burners bb, and this mixture of gas and air produces 15 extensively hot flames, consuming only a comparatively very small quantity of gas. The supply of gas and air is regulated by valves Ab and Ad, set in the gas-main and in the secondary pipes, respectively, and by a valve (not 20 shown in the drawings) in the main air-pipe. A draft of air passes into the heater through opening Da, and is regulated by sliding shutter Ds and damper Ed, set in the main flue E, leading into the chimney.

30 For burning of oil the apparatus shown in Figs. 12 and 13 is designed. It consists of a square tank Bo, made of wrought-iron and covered air-tight by lid Bl, fastened upon it by bolts around its flanged rim. In this tank, 35 set in the lower part of the furnace and covered with a layer of non-conducting material, crude oil, as used for firing boilers, is filled through pipe Po, entering near the bottom and provided with an automatic back-pressure 40 valve vo. Through pipe Pa, entering the tank near the top, compressed air is driven into the space above the level of the oil, and by the pressure of this air the oil is driven upward in the tube st of the burner Sp and in the flat 45 tubes Tt extending from the tank into the heater. In tubes Tt, which reach considerably lower than spray-burner Sp, wicks of loosely-woven asbestos fabric are inserted to prevent overflowing of the oil from them.

50 A draft of air passing into the heater through opening Oo, above the covering of the tank, flows upward between the burners, as indicated by arrows, and the combustion-gases escape through flue er and through the 55 flues arranged between the walls into the chimney.

Burner Sp consists of tube st, with a finely-perforated crown cs set on top of it and air-tightly connected around its rim to air-pipe At. 60 The oil driven by the pressure of the air in tank Bo overflows on top of tube st upon the crown cs, and is evaporated by a strong current of air driven into pipe At and forcing its way through the crown. To prevent the burning 65 of the oil upon the crown cs, the head of the sprayer is inclosed with a hood of wire-cloth. The air, saturated with the vapors of

the oil, passes through this hood into the heater, where it burns, producing a high-rising and very hot flame. 70

The firing is regulated by increasing or reducing the pressure of air in tank Bo and by increasing or reducing the draft through the heater. Burners Tt are effective in heating the lower part of the walls of the baking-chamber, thus supplementing the burner Sp, heating principally the upper part. It will be seen that in this manner every part of the baking-chamber will be thoroughly and equally heated with the least possible quantity of fuel, the heat radiating from the center toward the sides and the double walls effectively preventing every loss of heat and consequent reduction of the temperature within the baking-chamber. 80 85

The baking-chamber extends upward and opens near the bottom. Thus the vapors rising from the dough cannot escape through the door, being also barred by the shelves, filling closely the area of the baking-chamber. 90 These shelves carrying the wares move from the opening upward, and the wares reach the space near top of the baking-chamber, where these vapors and heat concentrate in such time when they will be mostly benefitted by 95 them.

Pyrometer H' is set above the door of the baking-chamber safely insulated from the walls, and pyrometer H² near the top of the baking-chamber, where the temperature will 100 be highest. Through tube K, provided with cock-valve K', operated by rods K² and K³, and connecting baking-chamber C with top flue E, superabundant vapors accumulated in the baking-chamber are released. 105

To enable the operator to oversee the process of baking, tubes o', o², and o³, provided with mica panes, are laid through the outer and inner walls of the baking-chamber, incandescent lights i', i², and i³, operated by switch N, producing the necessary illumination. 110

Main flue E, leading into the chimney, is closed by damper Ed, whose construction is shown in Fig. 6. This damper regulates the draft through all parts of the oven, and consists of a hollow square cylinder dv, fitted into the flue E and set on lid dp. All four sides of this cylinder dv are perforated by alternately-arranged apertures da and riveted to lid dp, overlapping the opening into the flue E. Lid dp is cast of iron, and additional weight may be placed inside the cylinder dv to weigh the damper down. Bell-crank ll pushes it upward when rod t is drawn, as indicated by arrow r'. Rod t is fastened on studs set in board Ks, thus setting damper Ed in such position producing the draft as may be required. This and all other dampers closing and regulating draft through the flues between the walls are operated from the front side of the oven where the furnace opens to enable the fireman to regulate the heating of the oven without interfering with the baker. 120 125 130

Fermenting-chamber F is provided beneath the oven and heated by hot water circulating from boiler D through pipes h laid on its bottom. This fermenting-chamber is built sufficiently long to allow a full charge for the oven (about thirty pans) to be filled in, the wares to rise while another charge is baked.

The wares are conveyed through the fermenting-chamber and through the oven on tracks T, shelves S being detachably suspended from carriers R, consisting of axis r and rolls r' and r^2 , and connected by links w .

Rolls r^2 move upon tracks T, secured to the walls of the fermenting-chamber, and from there the carriers are lifted by wheel W' , hooks v catching the axis r on both ends between the roll r' and link w upon the track T'. It will be observed that the curved ends of these rails rise gradually over the wheel W , and thus as each carrier is moved forward upon them its axis r is automatically lifted out of the hooks. Rails T' are supported upon pillars t to make the wares accessible to the baker, finishing during their move upon these tracks their preparation for baking.

Wheel W^2 in the opening of the baking-chamber is similarly equipped, though correspondingly smaller than wheel W . This wheel W^2 transmits the carriers R with shelves S from rails T' into the baking-chamber, wherein they hang suspended on links w from the top rails T ^{2} and are drawn over these rails (or held so suspended, as the case may require) by wheels W^3 , which also transmit the carriers R with shelves S from the baking-chamber upon track T ^{3} , similarly arranged as track T'.

Wheels W^2 and W^3 are made to correspond in circumference to the length of links w , connecting the carriers. On the axes of these wheels a disk is set, to which a pawl is adjustably attached, operating a ratchet-wheel of the counting-machine z , set on the outside wall of the bake-oven and indicating the number of shelves passed into or out of the baking-chamber. Dial X, with set hands, is placed on one side of the indicator Z, and on other side a clock Y to facilitate the regulation of the baking process by the operator.

Wheels W' , W^2 , W^3 , and W^4 , transmitting carriers R with shelves S from the fermenting-chamber and through the baking-chamber, are revolved by a worm-gear, the spirally-toothed wheels u being keyed to shafts s and driven concurrently by worms u' , or by hand-power by levers lu , to which pawls pw are attached, operating ratchet-wheels rw set on the shafts of wheels W' and W^4 , the ratchet-wheels rw and pawls pw serving also the purpose of arresting the backward motion of these wheels and thus sustain the carriers R with shelves S, suspended from rails T ^{3} in the baking-chamber when their motion is stopped.

In Fig. 1 I have also shown a device for emptying the pans while the carriers travel on track T ^{3} . Basket Rc , having a rack q set

in the bottom, is placed beneath the shelves, so that the rack will stop each shelf as it is moved along and, swinging it out of its horizontal position, will cause the baked wares to slide from the pan into the basket. Shelves with wares that would not bear such handling are detached on the end of track T ^{3} from the carriers and transmitted to carriers on track T ^{4} . Shelves with new wares are attached to the carriers during their transmission on the wheels W^4 from track T ^{3} to track T in the fermenting-chamber. Shelves with wares not requiring raising by fermentation, are set upon the carriers on wheels W' and passed directly into the baking-chamber.

I claim as new and of my invention and desire to secure by Letters Patent—

1. A bake-oven, comprising a baking chamber, having double walls on all sides, and double decking, and closed against the furnace and flues; a heater set in center of the baking chamber and extending into it, and a furnace beneath this heater, having flues leading directly into chimney and provided with dampers whereby these flues may be partly or wholly closed, and with a register connecting the furnace with the heater and admitting hot gases, produced by the combustion of fuel, to pass through the heater and through flues provided between the inner and outer walls inclosing the baking chamber.

2. In a bake-oven, the combination with a baking chamber, inclosed by double walls on all sides, of a heater, set in center of the baking chamber and capable of being heated by oil or gas burners arranged within the heater, the hot gases, produced by combustion of the fuel passing through the heater and through flues provided in the space between the inner and the outer walls inclosing the baking chamber.

3. The combination with a bake-oven, having double walls, of a boiler set closely to the heater between the walls and between the flues conducting the hot gases from the furnace, and of pipes, conducting water to and from the boiler, for the purpose of utilizing the heat of gases passing from the heater, for heating a supply of water required for preparing dough and for heating a fermenting compartment for raising the wares.

4. The combination with a bake-oven, having inner and outer walls and a baking chamber closed against the furnace and flues, provided in the space between the inner and the outer walls inclosing the baking chamber, and a double top, communicating with main flue to the chimney, of a damper, regulating the draft through the furnace, through the heater and flues and consisting of a hollow cylinder open on top and perforated on sides, set upon a lid, overlapping the opening into the flue and operated by a bell crank and a rod attached to it.

5. In a bake-oven, the combination with a damper, regulating the draft through the furnace, through the heater and flues and oper-

ated by a bell crank and a rod attached to it, of a board with studs adapted to hold the rod in position to produce any required draft.

6. The combination with a bake-oven, having a heater set within the baking chamber and a furnace beneath the heater and provided with a register, admitting hot gases into the heater, of flues, provided with dampers and connecting the furnace directly with the main flue and thus capable of producing strong draft, necessary when fire is started.

7. In a bake-oven, comprising a baking chamber with a heater set within the baking chamber and a fermenting compartment arranged beneath, the combination with carriers consisting of two grooved rolls set upon an axis from which shelves with wares are detachably suspended, and connected by links into a flexible train, of rails affixed to the walls of the fermenting compartment and of the baking chamber, and forming suitable tracks over which these carriers are drawn.

8. In a bake-oven, comprising a baking chamber with a heater set within the baking chamber and a fermenting compartment arranged beneath, the combination with carriers from which shelves with wares are detachably suspended, and connected by links into a flexible train of wheels keyed to shafts and provided with hooks in corresponding position, adapted to take up the axes of the carriers between the rolls and their connecting links and thus pull them over rails on which these carriers travel, and to transmit them from one track to another.

9. In a bake-oven, comprising a baking chamber with a heater set within the baking chamber and a fermenting compartment arranged beneath, the combination with carriers from which shelves with wares are detachably suspended, and connected by links into a flexible train, of wheels provided with hooks adapted to take up, move and transmit the carriers, of spirally toothed wheels keyed to the shafts and driven concurrently by worms, and of levers with pawls attached thereto, operating ratchet wheels, set on the shafts of the transmitting wheels, these pawls being adapted to move the transmitting wheels by hand power and to arrest their backward motion, thus sustaining the carriers with shelves suspended from the rails in the baking chamber.

10. In a bake-oven, adapted for a continuous baking process and provided with a counting machine, the combination with wheels, transmitting carriers into, and out of the baking chamber, and corresponding in the extent of their circumference to the length of links connecting the carriers, of a disk, set on the shaft of these wheels and carrying a pawl adjustably attached to it and operating the counting machine, to indicate the number of shelves transmitted into or out of the baking chamber.
